UNITED STATES PATENT OFFICE.

FREDERICK A. GESKING, OF CHICAGO, ILLINOIS, ASSIGNOR OF ONE-HALF TO REUBEN KROMER, OF CHICAGO, ILLINOIS.

MUSIC-LEAF TURNER.

1,057,418.

Specification of Letters Patent.

Patented Apr. 1, 1913.

Application filed March 4, 1912. Serial No. 681,356.

To all whom it may concern:

Be it known that I, FREDERICK A. GESKING, a citizen of the United States, and a resident of the city of Chicago, county of Cook, and State of Illinois, have invented 5 certain new and useful Improvements in Music-Leaf Turners, of which the following is a specification.

My invention relates to improvements in 10 music leaf turners, and has for its object the provision of a device of this character of simple construction and efficient in operation.

The invention consists in the combinations 15 and arrangements of parts hereinafter described and claimed.

The invention will be best understood by reference to the accompanying drawings forming a part of this specification, and in 20 which—

Figure 1 is a front elevation of a music leaf turner embodying my invention, Fig. 2, a partial side elevation of the same, and Fig. 3, a partial top plan view of the same.

The preferred form of construction, as 25 illustrated in the drawings, comprises a frame made up of a center strip 1, two side wires 2 and a bottom piece 3, all secured together, as shown. Bottom piece 3 is in the 30 form of an angle iron, and has one leg 4 extending horizontally to constitute a shelf for the support of music sheets. A post 5 is arranged centrally on shelf 4 and music leaf holders 6 are pivotally mounted on said 35 post by means of straps or loops 6'. Each of the music leaf holders 6 is substantially U-shaped in cross section to receive the edge 40 of the music leaf or sheet and is provided in its upper end with a spring catch 7 adapted to retain a music leaf therein. At its bottom 45 each of the holders 6 is provided with a radially extending arm 8 carrying a weight 9 at its outer end. A wire frame is hinged at 10 to the central portion of shelf 4 and is 50 provided with a series of vertical guide rods 11, as shown. Blocks 12 are mounted to reciprocate vertically upon guide rods 11 and 55 are connected with rods 8 by means of cords 13 which pass over guide rollers 14 in said 60 frame, as shown. Finger pieces 15 are also mounted to reciprocate on guide rods 11 and 65 are detachably connected with blocks 12 by 70 spring catches 16. Each of the spring 75

catches 16 is provided at its upper end with a notch 17 adapted to engage the corresponding block 12 and inclined surfaces 18 and 19 arranged at each side of said notch. A stop bar 20 is secured across guide rods 11, as indicated, and is adapted to engage inclined 80 surface 19 on each of the spring catches 16 at the lower terminal of the movement of the corresponding finger piece 15 and force 85 said catch out of engagement with the corresponding block 12.

In use, the music leaves to be turned are 90 secured in holders 6 and arranged in the usual manner for playing. When it is desired to turn the first sheet, the finger piece 15 shown at the left of Fig. 1, is depressed. Depression of this finger piece carries the 95 corresponding block 12 and thus causes the corresponding cord 13 to operate the corresponding arm 8 to cause a partial rotation thereof. When the arm and holder reach the medial position, the inclined surface 19 100 on the corresponding spring catch 16 engages bar 20 to release the corresponding block 12, so that as arm 8 swings past the medial position, block 12 is automatically 105 released and the inertia of the corresponding weight 9 continues and completes the movement of the holder and leaf. When it is desired to turn the other sheet, the other finger 110 piece is depressed and the same operation takes place. Springs 21 serve to return 115 finger pieces 15 to their upper positions, whereupon inclined surfaces 18 serve to cause reengagement of notches 17 with the corresponding blocks 12.

While I have illustrated and described the 120 preferred form of construction for carrying my invention into effect, this is capable of variation and modification without departing from the spirit of the invention. I, therefore, do not wish to be limited to the 125 exact details of construction set forth, but desire to avail myself of such variations and modifications as come within the scope of the appended claims.

Having described my invention, what I 130 claim as new and desire to secure by Letters Patent is:

1. A music leaf turner comprising a 135 frame; a leaf holder rotatably mounted on said frame; operating means connected with 140 said holder to swing the same through a por-

tion of its movement; and automatic means for disconnecting said operating means from said holder at the end of the operative movement of said operating means, substantially as described.

2. A music leaf turner comprising a frame; a leaf holder rotatably mounted on said frame; a radially extending arm on said holder; a weight at the outer end of said 10 arm; operating means connected with said holder to swing the same through a portion only of its movement; and automatic means for disconnecting said operating means from said holder at the end of the operative movement of said operating means, substantially 15 as described.

3. A music leaf turner comprising a frame; a leaf holder rotatably mounted on said frame; a weight on said holder; a 20 slideable block mounted on the frame; a flexible connection between said block and said holder; a finger piece detachably connected with said block; and automatic means for disengaging said finger piece from said 25 block at the end of the operative movement of said finger piece, substantially as described.

4. A music leaf turner comprising a frame; a leaf holder rotatably mounted on 30 said frame; a radially extending arm on said holder; a weight at the outer end of said arm; a slideable block mounted on the frame; a flexible connection between said block and said holder; a finger piece detachably connected with said block; and automatic means 35 for disengaging said finger piece from said block at the end of the operative movement

of said finger piece, substantially as described.

5. A music leaf turner comprising a 40 frame; a leaf holder rotatably mounted on said frame; a weight on said holder; a slideable block mounted to reciprocate in the central lower portion of said frame; a flexible operative connection between said block and 45 said holder; a reciprocatory finger piece; a spring catch on said finger piece and detachably engaging said block; and a stationary stop arranged to disengage said spring catch from said block at the end of the operative 50 movement of said finger piece, substantially as described.

6. A music leaf turner comprising a frame; a leaf holder rotatably mounted on 55 said frame; a radially extending arm on said holder; a weight at the outer end of said arm; a slideable block mounted to reciprocate in the central lower portion of said frame; a flexible operative connection between said 60 block and said holder; a reciprocatory finger piece; a spring catch on said finger piece and detachably engaging said block; and a stationary stop arranged to disengage said spring catch from said block at the end of the operative movement of said finger piece, sub- 65 stantly as described.

In testimony whereof I have signed my name to this specification in the presence of two subscribing witnesses.

FREDERICK A. GESKING.
